UNITED STATES PATENT OFFICE.

HENRY I. WRIGLEY, OF CHICAGO, ILLINOIS, ASSIGNOR TO UNIVERSAL DRAFT GEAR ATTACHMENT CO., OF CHICAGO, ILLINOIS, A CORPORATION OF ILLINOIS.

DRAFT-PLATE FOR RAILWAY-CARS.

1,164,696.

Specification of Letters Patent. Patented Dec. 21, 1915.

Original application filed August 16, 1913, Serial No. 785,055. Divided and this application filed May 18, 1914. Serial No. 839,375.

To all whom it may concern:

Be it known that I, HENRY I. WRIGLEY, a citizen of the United States, and resident of Chicago, county of Cook, and State of Illinois, have invented certain new and useful Improvements in Draft-Plates for Railway-Cars, of which the following is a specification, and which are illustrated in the accompanying drawings, forming a part 10 thereof.

This application is a division of my application, Serial No. 785,055, filed August 16, 1913.

This application relates to draft arms for railway cars of the type adapted to be attached to the car sills and be provided with draft and buffering shoulders and intermediate limiting stops for defining the degree of compression of the draft gear; the invention appertaining particularly to the form 20 of construction of the limiting stops.

The invention is fully hereinafter described and is illustrated in the accompanying drawings, in which—

Figure 1 is a detail plan view, partially in section, of a portion of a railway car with an improved draft plate applied thereto; Fig. 2 is an inside elevation of one of the plates; Fig. 3 is a detail in perspective of a 25 portion of the plate showing one of the limiting stops, some portions being broken away, and Fig. 4 is a detail in perspective of the same portion of the plate, from a different point of view.

The draft plate 10 is ordinarily made of cast metal and comprises a body portion adapted to fit against the inner face of a draft sill, as 11, and to be secured thereto by means of bolts. The body portion of the 35 plate comprises a series of offset longitudinally extending sections, as 12, 13, but this feature is not herein claimed, as it is made the subject of the parent application of which this is a division. The improved 40 limiting stop is not dependent upon this specific form of the body portion of the plate but is adapted for use in connection with draft plates of other forms.

The draft plate here shown is adapted for 50 use in connection with so-called tandem draft gears there being provided 2 sets of

draft and buffering shoulders 14, 15 and 16, 17, but the invention for which protection is sought is not limited to this feature.

The improved limiting stop comprises a 55 pair of flanges 18, 19, outstanding from and preferably formed integral with the body portion of the plate 10. Each of these flanges takes the form of a parallelogram. The two flanges are in vertical alinement 60 and are spaced apart, one being above and the other below the longitudinal median line of the plate. Adjacent walls 20, 21 of the two flanges are united by a web 22 which forms a guide bearing for the spring of the 65 draft gear. The several walls of the flanges 18, 19 and the web 22 are preferably of uniform thickness and substantially the same thickness of the body of the plate 10. The form of the stop and its disposition with 70 reference to the body of the plate are such that T-sections are avoided, thereby the casting operation is facilitated and an improved product obtained, as the substantial uniformity of thickness of metal in the various 75 parts avoids the danger from a variable shrinkage.

The web 22 may be apertured, as shown, to permit the insertion of an attaching bolt for securing the arm to the sill. 80

I claim as my invention,—

1. A draft plate having a follower limiting stop integral with the body of the plate and comprising a pair of vertically arranged instanding flanges, each flange forming a 85 parallelogram, the sides of which are of uniform height throughout, one of the horizontal sides of one of the flanges being laterally extended to form a guide bearing for a draft spring. 90

2. A draft plate having a follower limiting stop integral with the body of the plate and comprising a pair of vertically arranged instanding flanges, each flange forming a parallelogram, and a web uniting adjacent 95 sides of the parallelograms to form a guide bearing for a draft spring.

HENRY I. WRIGLEY.
